UNITED STATES PATENT OFFICE.

ROBERT R. HUGHES, JR., OF NEW YORK, N. Y., ASSIGNOR TO UNION SPECIAL MACHINE COMPANY, OF CHICAGO, ILLINOIS, A CORPORATION OF ILLINOIS.

RUFFLING MECHANISM FOR SEWING-MACHINES.

1,334,611.

Specification of Letters Patent.

Patented Mar. 23, 1920.

Application filed November 18, 1915. Serial No. 62,154.

To all whom it may concern:

Be it known that I, ROBERT R. HUGHES, Jr., a citizen of the United States, residing at New York, in the county of New York, 5 State of New York, have invented certain new and useful Improvements in Ruffling Mechanism for Sewing-Machines, of which the following is a description, reference being had to the accompanying drawing and 10 to the figures of reference marked thereon.

The invention relates to new and useful improvements in ruffling mechanisms for sewing machines, and more particularly to a ruffling mechanism which may be thrown 15 into and out of operation at the will of the operator and without stopping the stitching mechanism.

An object of the invention is to provide a sewing machine having means for disconnecting the ruffling blade from its actuating mechanism with controlling devices for preventing the disconnection of said ruffling blade when said ruffling blade is on its forward or rearward movement.

25 A further object of the invention is to provide a ruffling mechanism of the above character having manually controlled means for rendering the ruffling blade ineffective and for moving the same to inoperative position, with means for preventing the shifting of the said manually controlled means except when the ruffling blade has been moved forward to form a ruffle.

A still further object of the invention is 35 to provide a ruffling mechanism of the above character having mechanism for automatically rendering the ruffling blade ineffective and for moving the same to inoperative position when the controlling means, *i. e.*, the 40 treadle, is released by the operator, with means for preventing the shifting of said automatic mechanism when the ruffling blade is moving forward for forming a ruffle, or moving backward after the ruffle has been 45 formed.

These and other objects will in part be obvious and will in part be hereinafter more fully disclosed.

In the drawings, which show by way of 50 illustration one embodiment of the invention:—

Figure 1 is an end view of a machine embodying my improvements;

Fig. 2 is a rear view of the machine;

55 Fig. 3 is a vertical sectional view show-

ing the means for vibrating the ruffling blade, the means for rendering the same effective or ineffective, and the automatic controlling mechanism therefor;

Fig. 4 is a similar view but with certain 60 of the parts omitted to show the automatic controlling mechanism in side elevation and with the parts shifted to position for rendering the ruffling blade ineffective;

Fig. 5 is a front view of the forward end 65 of the machine, parts being broken away to show the looper;

Fig. 6 is a view more or less diagrammatically showing the ruffling blade in extreme rear position;

Fig. 7 is a similar view but showing the 70 ruffling blade in its forward position;

Fig. 8 is a view, more or less diagrammatically, showing a treadle for controlling the ruffling mechanism; and

Fig. 9 is a detail showing in side elevation a portion of the operating yoke for the ruffling blade.

The ruffling mechanism, together with the means for rendering the same effective and 80 ineffective at the will of the operator is similar to that shown in the patent granted to Russel G. Woodward, July 31st, 1900, No. 655,143.

In this patent, there is disclosed a sewing 85 machine having a ruffling blade attached thereto which is moved back and forth by suitable mechanism including devices whereby the operator at will may render said ruffling blade effective or ineffective and, when 90 said blade is rendered ineffective, the vibrations thereof cease and said blade is moved rearwardly away from the needle. When the controlling lever is shifted in one direction 95 in the patented structure, the ruffling blade is coupled to its actuating mechanism and, when said controlling means is moved in the opposite direction, then the ruffling blade is disconnected from its actuating mechanism.

The present invention consists primarily in providing devices which will prevent the disconnecting of the ruffling blade from its actuating mechanism while said blade is moving forward to form a ruffle or is on its 105 backward movement.

Referring in detail to the drawings, I will describe briefly the ruffling machine to which my controlling devices have been applied. Said ruffling machine consists of a work sup-

100

105

110

port 1, an overhanging arm 2 in which reciprocates a needle bar 3 carrying, as herein shown, a single needle 4. Said needle bar is reciprocated by a needle lever 5. Coöperating with the needle beneath the work support is a looper 6 mounted on a looper support 7, and this looper support is oscillated by a link 8. The material is fed over the work support by a feed dog 9. The presser foot 10 coöperates with said feed dog.

Located in front of the needle is a fabric manipulating implement, such as a ruffling blade 11, which is mounted on a carrier 12 pivoted to a supporting head 13 on the forward end of a reciprocating rod 14. This rod is mounted in bearings 15 and 16. The rod 14 is reciprocated back and forth to give the ruffling stroke to the ruffling blade 11, by a rock shaft 17 which carries a downwardly projecting arm 18 connected by a link 19 to a bracket 20 fixed to the bar 14. This rock shaft 17 is mounted in suitable bearings 21 and 22. Said shaft is provided also with a rearwardly extending arm 23. Pivoted to the outer end of the arm 23 is a link 24. This link 24 is pivoted at its lower end to a sliding block 25.

An oscillating yoke 26 is pivoted at 27 to the supporting bed of the machine, and this yoke coöperates with an eccentric 28 mounted on the main shaft 29. Said yoke is provided with a rib 26^a adapted to engage the recess 30 in the block 25, when said block is moved to the right, as viewed in Fig. 3. When, however, the block is moved to the left, as shown in Fig. 4, it is disengaged from this rib and the yoke will vibrate without imparting movement to the link 24. When said sliding block engages the rib, then movement will be imparted to the link 24 and through the rock shaft 17 will reciprocate the rod 14 carrying the ruffling blade 11.

Journaled on the shaft 17 is a yoke 31. This yoke is connected by a pin 32 to an arm 33 which is loosely journaled on the outer end of the rock shaft 17. Said arm 33 is connected by a link 34 to the block 25 so that, when the arm 33 is moved to the right, as viewed in Fig. 3, it will force the sliding block 25 to the right, causing the same to engage the rib of the oscillating yoke 26 and thus connect the ruffling blade to its actuating mechanism. When the arm 33 is moved to the left, then the ruffling blade will be disconnected from its actuating mechanism.

A leaf spring 35 is fixed to a bracket 36 carried by the bed of the machine, and the upper end of this spring bears against a pin 37 carried by the arm 33. This spring normally forces the arm 33 to the left, as viewed in Figs. 3 and 4, and serves as automatic means for disconnecting the ruffling blade from its actuating mechanism.

65 Mounted in a suitable bearing 38, carried

by the standard of the machine, is a rock shaft having an arm 39 connected by a suitable flexible member to a treadle 41. A spring 42 may be placed under the treadle for normally raising the rear end 70 of the treadle when released by the operator. This rock shaft carrying the arm 39 also carries a second arm 43 on the outer end of which is mounted a roller 44 adapted to engage a flat bearing face 45 on the arm 43. 75

When the treadle is depressed by the operator, the rock shaft connected thereto will be actuated and the arm 43 will press the roller 44 against the arm 33 and this will shift the block 25 into engagement with the 80 rib and thus establish connection between the ruffling blade and its actuating mechanism. When the treadle is released, then the spring 35 comes into play to shift the arm 33 in the opposite direction. An adjustable 85 stop 46 engages the arm 33 and limits the inward movement thereof.

The yoke 31 has a downwardly projecting lug 60 to which is connected a link 61. This link 61 is pivoted to the upper end of the 90 lever 62 and the lever 62 has a plate 63 adjustably attached to its lower end. This plate is adapted to engage a cross pin 64 on the carrier 12 and swing the ruffling blade to inoperative position when said yoke 31 is 95 oscillated through the action of the spring 35 for disconnecting the ruffling blade from its actuating mechanism.

The above parts are in a general way similar to the devices shown and described 100 in the Woodward patent, above referred to, except as to the detail mechanism for shifting the arm 33 for rendering the ruffling mechanism effective. In the device herein shown, the depending arm 33 has a loose 105 connection with the arm 43. This, however, is the full equivalent of the mechanism shown in the patent and is no part of the present invention.

It will readily be seen from the above description that, when the operator releases the treadle, the spring 35 will at once shift the parts so as to render said ruffling blade ineffective by disconnecting the same from its actuating mechanism and, at the same 115 time, shift said ruffling blade to inoperative position.

The rib 26^a, with which the block 25 engages, is curved on an arc of a circle struck from a center located at the pivotal connection between the link 24 and the arm 23 when said arm 23 is raised and the ruffling blade is at the forward end of its stroke. A movement of the block 25 along this rib 26^a, when the ruffling blade is at the forward end 125 of its stroke, will have no effect on the operating mechanism for the ruffling blade owing to this concentric positioning of the parts. When, however, the yoke 26 is lowered to its extreme lowest position, said rib will 130

then be set eccentrically relative to the pivotal connection between the arm 23 and the link 24, and a movement of the block on the rib will shift the arm 23 although the parts 5 of the machine may be at rest. Furthermore, the rib 26^a and the block 25 are so constructed and located that, when the yoke 26 moves away from its concentric position, a movement of the block along the rib to 10 toward the fulcrum of the yoke will cause the ruffling blade to move forward, although this forward movement of the ruffling blade is not quite a full stroke of the ruffling blade. From the above, it will be apparent, 15 therefore, that, if this block 25 is shifted when the ruffling blade is at the rear end of its stroke, or at any intermediate point between the rear end of its stroke and the forward end of its stroke, it would cause a forward 20 kick or movement of the ruffling blade. This movement, however, will form an incomplete or partial ruffle, which will not be caught by the stitching mechanism. Furthermore, the operator usually holds the 25 strip being ruffled, and a forward kick of the ruffling blade is apt to mark or tear the fabric, and, when it is flattened out, if the incomplete ruffler is not stitched, then the fabric shows an objectionable mark. Furthermore, the operator often marks the 30 fabric being ruffled and the unruffled fabric with the desire of gathering the fabric so as to take out the fullness and bring the marked sections directly together. When 35 this operation is completed, that is, the fullness has been taken out, the operator is holding the fabric tightly, and if a false movement of the ruffling blade, as above described, occurs, the fabric being held tightly 40 is likely to be badly marked or torn, as has been referred to. Therefore, it will be noted that, if the mechanism for shifting the block 25 can be operated at any time during the stroke of the ruffling blade, objectionable 45 movements of the ruffling blade may occur.

When the block 25 is at its extreme left hand position, as viewed in Figs. 3 and 4, said block is entirely disconnected from the rib 26^a. Also at this time the yoke 31 is 50 swung so as to move the arm 60, see Fig. 1, to the left, as viewed in said figure, and this swings the lever 62 so that the plate 63 engages the carrier 12 supporting the ruffling blade, and this moves the ruffling blade to 55 the rear end of its stroke and tilts the same upwardly, as fully shown and described in the patent. The block 25 is permitted to move upwardly when disengaged from the rib 26^a, and the rib 26^a has a tapered nose 60 26^b at its left hand end, as viewed in Fig. 9, and this permits the block to make engagement with the rib when it is moved to the right by the operator. In other words, while the block 25 has more or less of a free movement up and down, it never moves to such

a distance but what it may be readily brought into engagement with the rib.

The main purpose of the present invention is to provide controlling devices which will prevent this formation of a partial or incomplete ruffle, and the resulting marking or tearing of the fabric, and to this end I have provided the arm 33 with a forwardly projecting bracket 47 which is secured to the arm by suitable screws 48. Said bracket 70 on its lower face is formed with a series of teeth 49. A lever 50 is pivoted to the standard of the machine at 51 and carries a pawl or holding dog 52. This lever at its lower end bears against a three-sided cam 53 80 mounted on the main shaft 29. A spring 54 secured to the lower end of the lever 50 and to the bed of the machine holds the lever pressed against the cam 53. The pawl or holding dog 52 is so positioned in the lever 85 that when the lower end is thrown to the left, as shown in Fig. 4, said pawl is out of the path of movement of the teeth 49 on the lower face of the bracket 47. When either side α or β of the cam 53 is in contact with 90 the lower part of the lever 50, then the pawl or holding dog 52 will be raised by the spring 54 into the path of the teeth and will engage the same, as shown in Fig. 3. The pawl 52 is fixed to the lever 50 and the 95 spring 54 permits the lever to yield when engaged by the side α of said cam 53 so that the arm 33 may be moved to the right and the teeth pass over the pawl, which is tapered at 55 for this purpose.

The cam 53 is so shaped and timed that the pawl or holding dog 52 will be in position for engaging the bracket during substantially the entire forward and rearward movement of the ruffling blade. Let us assume that the operator releases the treadle while the ruffling blade is moving forward. At this time, this pawl or holding dog 52 is raised and engages the teeth 49 formed in the bracket 47 and although the treadle may 100 be raised by the action of the spring underneath the same, this pawl or holding dog 52 will prevent the spring 35 from throwing the arm 33 to disconnect the ruffling blade from its actuating mechanism until 105 the main shaft is turned a sufficient distance to lower the pawl or holding dog 52 and release the arm 53.

The same action occurs on the rearward movement of the ruffling blade. If the 110 treadle is released and raised by the action of the spring underneath the same, the pawl or holding dog 52 will prevent the spring 35 from throwing the arm 33 to disconnect the ruffling blade from its actuating mechanism until the main shaft is turned a sufficient distance to carry the ruffling blade to the rear end of its stroke and then forward to substantially the forward end of its 115 stroke. In other words, the machine is pro- 120

vided with automatic means for disconnecting the ruffling blade from its actuating mechanism, and this pawl or holding dog, together with its coöperating devices, will 5 prevent this automatically shifting mechanism from disconnecting the ruffling blade from its actuating mechanism at all times, except when the ruffling blade is substantially at the forward end of its stroke and 10 this in turn prevents the undesirable movements of the ruffling blade above referred to, which might produce partially formed tucks or ruffles, or perhaps tear the fabric.

While I have described my invention as 15 applied to a ruffling machine for preventing the release of the ruffling blade while it is on its forward or rearward movement, it is understood that the invention may be equally applied to any other type of feeding 20 element for manipulating the fabric so as to prevent the same from being rendered ineffective while it is on its feeding stroke. I have, therefore, used the term ruffling blade simply as a descriptive term and not 25 as a limiting term, throughout the specification and claims.

It is obvious that minor changes in the details of description and arrangement of parts may be made without departing from 30 the spirit of the invention, as set forth in the appended claims.

Having thus described my invention, what I claim as new and desire to secure by Letters-Patent is:—

35 1. A sewing machine including in combination, a work support, a main feed dog, a fabric manipulating implement coöperating with said feed dog, means for vibrating said fabric manipulating implement to feed the fabric, and manually controlled means 40 for disconnecting said fabric manipulating implement from its vibrating means, and devices for preventing the operation of said last-named means while said fabric manipulating implement is on its feeding movement.

50 2. A sewing machine including in combination, a work support, a main feed dog, a ruffling blade coöperating with said feed dog, means for vibrating said ruffling blade, manually controlled means for disconnecting said ruffling blade from its vibrating mechanism, and means for preventing the disconnection of said ruffling blade from its 55 vibrating mechanism while said ruffling blade is moving forward or backward.

3. A sewing machine including in combination, a work support, a main feed dog, a ruffling blade coöperating with said feed dog, means for vibrating said ruffling blade, manually controlled means for connecting the ruffling blade with its vibrating mechanism, automatic means for disconnecting the ruffling blade from its vibrating mechanism when released by the operator, and de- 60

vices for preventing the operation of said automatic means while said ruffling blade is moving forward to form a ruffle.

4. A sewing machine including in combination, a work support, a main feed dog, 70 a ruffling blade coöperating with said feed dog, means for vibrating said ruffling blade, manually controlled means for connecting the ruffling blade with its vibrating mechanism, automatic means for disconnecting the 75 ruffling blade from its vibrating mechanism when released by the operator, and devices for preventing the operation of said automatic means while said ruffling blade is moving forward to form a ruffle, said devices operating to release the automatic means when said ruffling blade reaches the forward end of its stroke.

5. A sewing machine comprising in combination, a work support, a ruffling blade, 85 means for vibrating said ruffling blade including a vibrating yoke, a link having a shiftable connection with said yoke whereby said link may be vibrated by the yoke or moved to ineffective position, manually controlled means for shifting the link for connecting the same with said vibrating yoke, automatic means for shifting said link in the opposite direction to disconnect the same from the yoke when released by the operator, 95 and devices for preventing the operation of said automatic means while said ruffling blade is forming a ruffle.

6. A sewing machine comprising in combination, a work support, a ruffling blade, 100 means for vibrating said ruffling blade including a vibrating yoke, a link having a shiftable connection with said yoke whereby said link may be vibrated by the yoke or moved to ineffective position, manually controlled means for shifting the link for connecting the same with said vibrating yoke, 105 automatic means for shifting said link in the opposite direction to disconnect the same from the yoke when released by the operator, a bracket carried by said link, a locking pawl for engaging said bracket while the ruffling blade is moving forward or backward for preventing the automatic shifting of the link.

7. A sewing machine comprising in combination, a work support, a ruffling blade, means for vibrating said ruffling blade including a vibrating yoke, a link having a shiftable connection with said yoke whereby 115 said link may be vibrated by the yoke or moved to inoperative position, manually controlled means for shifting the link for connecting the same with said vibrating yoke, automatic means for shifting said link 120 in the opposite direction to disconnect the same from the yoke when released by the operator, a bracket carried by said link and having a toothed under face, a locking pawl adapted to engage said toothed face for pre- 125

venting the shifting of the link while said ruffling blade is moving forward or backward.

8. A sewing machine comprising in combination, a work support, a ruffling blade, means for vibrating said ruffling blade including a vibrating yoke, a link having a shiftable connection with said yoke whereby said link may be vibrated by the yoke or moved to inoperative position, manually controlled means for shifting the link for connecting the same with said vibrating yoke, automatic means for shifting said link in the opposite direction to disconnect the same from the yoke when released by the operator, a bracket carried by the link and having a toothed under face, a lever, a pawl carried by said lever, and means for shifting said lever whereby said pawl is adapted to engage the teeth on said bracket to prevent the movement of the link while the ruffling blade is moving forward or backward.

9. A sewing machine comprising in combination, a work support, a ruffling blade, means for vibrating said ruffling blade including a vibrating yoke, a link having a shiftable connection with said yoke whereby said link may be vibrated by the yoke or moved to inoperative position, manually controlled means for shifting the link for connecting the same with said vibrating yoke, automatic means for shifting said link in the opposite direction to disconnect the same from the yoke when released by the operator, a bracket carried by the link and having a toothed under face, a lever, a pawl carried by said lever, and means for shifting said lever whereby said pawl is adapted to engage the teeth on said bracket to prevent the movement of the link while the ruffling blade is moving forward, said shifting means for

the lever operating to move the pawl from engagement with the teeth to permit the automatic shifting of the link when said ruffling blade reaches the forward end of its stroke or on its rearward movement.

10. A sewing machine including in combination, a work support, a fabric manipulating implement to feed the fabric, means for rendering said fabric manipulating implement effective or ineffective, said means including a normally stationary lever under the control of the operator, and means to prevent the operation of the lever except at a predetermined portion of the movement of the fabric manipulating implement.

11. A sewing machine including in combination, a work support, a fabric manipulating implement, actuating means for vibrating said implement to feed the fabric, said actuating means including a breakable connection, and devices including a latch dog for preventing the breaking of said connection during the feeding stroke of said implement.

12. A sewing machine including in combination, a work support, a fabric manipulating implement, actuating means for vibrating said implement to feed the fabric, said actuating means including a breakable connection, devices including a latch dog for preventing the breaking of said connection during the feeding stroke of said implement, and means for automatically releasing said latch subsequent to the feeding action of said implement.

In testimony whereof, I affix my signature in the presence of two witnesses.
